Fig. 5

Fig. 7

Fig. 4

Fig. 8

Fig. 6

FIG. 1 is a top plan view of a releasable clamp for a ground plate electrode showing my new design;

FIG. 2 is a left end elevational view of the clamp of FIG. 1;

FIG. 3 is a right end elevational view of the clamp of FIG. 1;

FIG. 4 is a rear elevational view of the clamp of FIG. 1;

FIG. 5 is a bottom plan elevational view of the clamp of FIG. 1;

FIG. 6 is a front elevational view of the clamp of FIG. 1;

FIG. 7 is a perspective view of the clamp of FIG. 1; and

FIG. 8 is a perspective view of the clamp of FIG. 1 showing the jaws of the clamp in an open position.

I claim:

The ornamental design for a releasable clamp for ground plate electrode, as shown.
